(57) **CLAIM**

The ornamental design of a desktop stand for a handset, as shown and described.

DESCRIPTION

FIG. 1 is a front view of a desktop stand for a handset showing my new design;

FIG. 2 is a perspective front view thereof;

FIG. 3 is a perspective rear view thereof; and,

FIG. 4 is a perspective front top view thereof.

The broken lines showing various disclaimed connectors, wiring and regions in the figures are for illustrative purposes only and form no part of the claimed design.

1 Claim, 4 Drawing Sheets

FIG. 1

FIG. 2

FIG. 3

FIG. 4
